(57) **CLAIM**

The ornamental design for a mobile phone, as shown and described.

DESCRIPTION

FIG. 1 is a top front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom front perspective view thereof.

The broken lines shown in the figures that are immediately adjacent the shaded areas and define unshaded regions represent the bounds of the claim. All other broken lines, including the features within broken line boundaries, the broken lines beneath the front glass, and the broken lines outside of the front face of the mobile phone on the sides, top, bottom or back, are directed to environment. The broken lines form no part of the claimed design.
